UNITED STATES PATENT OFFICE

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed September 25, 1922. Serial No. 590,371.

This invention relates to cash registers, and particularly to improvements in the type of machine shown in applicant's co-pending application for Letters Patent of the United States, Serial No. 293,141, filed April 28, 1919.

One of the objects of this invention is the provision of mechanism for carrying out the process of multiplication and for indicating the multiplicand and multiplier.

It is also an object to provide mechanism for accumulating the items of a transaction, for printing the total of the items, and for indicating the number of items entered at any time prior to a total printing operation.

Special objects of this invention are to carry out these provisions in connection with the type of register shown in said application; to employ the regular indicating means for indicating the multiplicand; to provide special indicating means only for the multiplier; to operate the special indicating means during each operation of the item entering means; to turn said special indicating means to zero during each total-taking operation; and to provide means for shifting the totalizer and its actuators relatively laterally to enter the amounts represented by the keys depressed in the proper totalizer wheels in processes of multiplication.

With these and incidental objects in view, the invention consists of certain novel features of construction and combinations of parts, the essential elements of which are set forth in appended claims, and preferred forms or embodiments of which are herein-after described with reference to the drawings which accompany and form part of this specification.

In the drawings:

Fig. 1 is a plan view of part of the machine.

Fig. 2 is a section taken on line 2—2 of Fig. 1.

Fig. 3 is a section taken through the totalizer.

Fig. 4 shows a portion of the rotary cam shaft.

Fig. 5 shows the mechanism for indicating the number of items entered and also for in-

dicating the multiplier in a multiplying operation.

Fig. 6 shows the mechanism shown in Fig. 5 in side elevation.

Fig. 7 shows the mechanism for setting up the letter M in a multiplying operation.

Fig. 8 is a detail view showing the cam shaft driving mechanism.

Fig. 9 is a section taken on line 9—9 of Fig. 1.

Fig. 10 shows the form of receipt issued during a multiplying operation.

Fig. 11 shows a portion of the detail strip.

Fig. 12 shows the form of receipt issued during an operation of the machine in which the total of items of a transaction is printed.

Fig. 13 shows the printer in elevation.

Figs. 14, 15, 16, 17 and 18 show a modified form of multiplying attachment.

Fig. 14 is a detail view of the pointer for showing the totalizer actuators selected for operation.

Fig. 15 shows the modified form of the invention in front elevation.

Fig. 16 shows the modified form of the invention in side elevation.

Fig. 17 is a detail view showing the driving connection between the keys and the totalizer actuators.

Fig. 18 is a plan view of the driving connections between the means directly adjusted by the keys and the totalizer actuators.

Fig. 19 shows another form of receipt.

The embodiments illustrated include the usual amount keys, means for indicating the amount set up on the keys, means for entering said amount in a totalizer and for printing the same, and means for printing the total of amounts entered. In addition,

mechanism is provided for shifting the totalizer and actuators relatively laterally or selectively rendering totalizer actuators effective and ineffective, for carrying out processes of multiplication by successive addition, and means for counting the number of items in a transaction and for setting up a multiplier in carrying out processes of multiplication.

In the embodiments illustrated, having particular reference first to Figs. 1 to 13, keys 30, arranged in denominational groups

85

90

95

100

as usual, are pivoted on a transverse rod carried by the side frames of the machine, and at their rear ends are notched to cooperate with a lip on a key coupler 31 for purposes well known in the art.

The rear ends of the keys are extended to cooperate with indicators 32, and also with pivoted key stops 33 which prevent a simultaneous depression of a plurality of keys in 10 a single denominational group.

Actuator controllers 34, (Fig. 2) connected to the rear ends of the keys of each denominational group, are provided with notches 35 for engaging rods 36 carried by 15 rocker frames 37, supported on a shaft 38. There is one frame 37 and rod 36 for each denominational group of keys. The units totalizer actuator 39 is directly secured to the rocker frame which is free on said shaft 38. The dimes totalizer actuator 39 and 20 rocker frame are secured to said shaft 38, as shown in Fig. 1. The notches in the actuator controllers 34 are located to transmit amounts of movement to the actuator proportionate to the number of units represented by the keys 30 to which the actuator controllers are connected.

The totalizer actuators 39 are normally in mesh with gears 40 which are connected with 30 the item type wheels 41 (Fig. 13) by a tube line 42 (Fig. 1) to set up the amounts represented by the keys depressed.

The key coupler 31, (Figs. 1, 2 and 8) before referred to, is pivotally mounted in the 35 side frames and rests upon the rear ends of the keys from which it receives its movement. The right hand end of the key coupler carries a roller 54 which cooperates with a slot in a driving rack 43 guided by a stud 44 projecting from the frame of the machine. The driving rack is provided with opposing 40 racks adapted to be thrown into mesh alternately with a gear 45 on a cam shaft 46 to rotate the shaft clockwise. The engagement 45 of the racks with the gear is effected and maintained by a spring 47, a spring-drawn pawl 48, a flange 49 on the rack, and a flange 50 on the frame, operating in the usual manner.

The cam shaft 46 (Fig. 9) extends through the right hand side frame. A cam 51 fixed to this shaft cooperates with a spring-pressed pivoted impression hammer supporting arm 52 curved to extend, through an opening in 55 the printer frame 53 (Fig. 13) into operative relation with the item type wheels 41. By means of this mechanism an impression is taken from the item type wheels 41 upon an issuing strip 55 during each item entering 60 operation.

The right hand end of the key coupler is provided with a trunnion 56 (Fig. 13) extending through the printer frame. An arm 57 fixed to the trunnion carries a spring 35 drawn pawl 58 which cooperates with a ratch-

et 59 secured to a feed roller 60 for feeding the issuing strip between the impressions made thereon. A spring tensioned roller 61 holds the strip in frictional engagement with the feed roller 60. An inking ribbon 62 is provided and may be fed by a feed roller 63 which may conveniently be driven by a pawl and ratchet (not shown) driven from the arm 57 as usual, or in any preferred manner.

The amounts represented by the keys depressed are also entered in a totalizer mounted in a frame 65 (Figs. 1, 2 and 3) pivotally and slidably supported on a rod 66 removably mounted in brackets projecting rearwardly from a front cross bar 67 secured to the side frames.

The totalizer elements (Figs. 2 and 3) include pinions 70 rigid with gear wheels 71 and ratchets 72 supported on a turn-to-zero shaft 73. The shaft is provided with a groove to cooperate with spring-pressed pawls on the totalizer elements to turn the totalizer to zero in the usual manner.

The totalizer pinions 70 are normally held disengaged from the actuators 39 by a cam 74 on the cam shaft 46, which cam 74 cooperates with rollers 75 on a lever 76 mounted on a pivot pin 77 on the totalizer frame 65 but held rigid with the frame by a pin 78. When a key is depressed the cam 74 is rotated clockwise whereby the lever 76 moves the totalizer pinions into mesh with the actuators.

For the purpose of effecting transfers each totalizer element is provided with a transfer trip projection 79 (Fig. 3) adapted to engage a projection nose on a transfer pawl supporting arm 80 to move the same out of supporting relation with respect to a transfer pawl 81, which may then move into engagement with the ratchet 72. This pawl 81 is pivotally supported on a transfer lever 82 rocked by a cam 83 (Fig. 4) on the cam shaft 46 during each item entering operation of the machine.

The amount accumulated in the totalizer is ascertained by a printing operation. For this purpose, mechanism is provided for setting up total type wheels 85 (Fig. 13) to print the amount in the totalizer. For this purpose also the totalizer has stepped disks 86 (Fig. 2) rigid with gear wheels 87 mounted on a rod in the totalizer frame 65 and meshing with the gears 71 rigid with the totalizer pinions 70.

The total type wheels 85 (Fig. 13) are located to the right of the printer frame 53 and are suitably supported therein and in a supplemental frame 88. These wheels are connected by a tube line 89 with gears 90 (Fig. 9) in mesh with segment-gears 91 rigidly connected with segment-gears 92 in mesh with segment-gears 93 connected by a tube line 94 (Figs. 1, 4 and 9) with the right hand legs of yokes 95 having their other legs 96 extended into feelers 99 adapted to be moved 120

into engagement with the steps on the disks 86 of the totalizer. The tube line is supported by a rod 98 supported in the printer frame and in a bracket 97 (Fig. 2) mounted 5 on the front cross bar 67. The steps on the stepped disks 86 are so located that the type wheels 85 will be set in accordance with the amount in the totalizer when the feelers 99 of the yokes 95 are moved into contact with 10 said disks.

Also rigid with the segment-gears 92 (Fig. 9) are other segment-gears 100 which mesh with segment-gear levers 101 provided with 15 hooks 102 supporting the upper ends of tension springs 103 attached to a rocking lever 104. The springs are normally restrained against moving the yokes 95 and total type 20 wheels 85 by a bar 105 connected by a link 106 to said rocking lever 104. The lever 104 is rocked first clockwise and then counter-clockwise by cams 107 secured on the driving shaft 108 driven by a gear 109 (Fig. 13) in mesh with a gear 110 driven by a crank or 25 motor, or any suitable means. As the rocking lever is moved clockwise to remove the bar 105 from the levers 101, the springs 103 are permitted to rock said levers and the 30 trains of segment-gears connected thereto until the feelers 99 contact with the disks 86 to set up the total type wheels 85 in accordance with the amount in the totalizer.

Impressions from the total type wheels 85 are taken upon the issuing strip 55 (Fig. 13) before referred to by a platen 112 carried by 35 an impression block 115. The block 115 also carries platens 113 and 114 cooperating with electros 116 and 117 respectively to print the matter shown at the top and bottom of a receipt shown in Fig. 10. The block 115 is flexibly supported on an arm 118 rigidly connected to a bell crank 119 carrying a roller at its lower end cooperating with a cam 120 secured to the shaft 108.

For the purpose of feeding the strip so that 40 the printed total amount thereon moves past a severing knife 125. (Fig. 13) a feed roller 60 is driven by a ratchet 126 (Fig. 9) connected to the feed roller shaft, and adapted to be operated by a pawl 127 carried by a plate 45 rigid with a pinion 128 in mesh with a segment-gear 129 driven from a roller 130 carried by an extension on the rocking lever 104.

It is also desirable to print the totals on a 50 detail strip 131 (Fig. 13) retained in the machine. The impression arm 132 for effecting this printing operation is driven by a link 133 connected to an arm 134 integral with the bell crank 119 before referred to. The detail strip 131 may be fed onto a receiving roll by 55 any suitable means operable during a total printing operation and may include an arm 135 bifurcated to cooperate with a pin 136 on a segment-gear lever 137.

Means is provided for returning the totalizer wheels to zero during a total printing op-

eration. This means includes, as one of its elements, the segment-gear lever 137 (Fig. 13) which is connected by a short link 138 with the link 106. This segment-gear lever meshes with a gear 139 secured on a shaft 140 70 (Fig. 9) which freely supports the segment-gears 91, 92 and 100. Secured to the shaft 140 on the left side of the printer frame is a segment-gear 141 (Fig. 9) which meshes with a gear 142 carrying a spring-pressed 75 pawl 143 cooperating with a ratchet 144 rigidly secured to a gear 145 in mesh with a gear 146. The gear 146 is mounted on a shaft 147 connected by a universal short shaft coupling 148 (Fig. 1) with the turn-to-zero shaft 73 of 80 the totalizer. Upon operation of the machine, the clockwise movement of lever 104 (Fig. 9) causes the pawl 143 to ride freely over the ratchet 144, and upon the return movement of lever 104, the pawl and ratchet 85 causes the shaft 147 to be rotated clockwise to reset the totalizer.

When resetting the totalizer wheels to zero, the transfer trip projections 79 (Fig. 3), as the totalizer wheels pass from "9" to "0", move the transfer pawl supporting arms 80, thus disengaging their shoulder from the transfer pawls 81. This would allow the transfer pawls 81 to swing downwardly and engage the ratchets 72 and move the totalizer 90 wheels one space as the transfer levers 82 operate, were not a device provided to hold the transfer pawls 81 in their normal positions during a zeroizing and total printing 95 operation. 100

This device consists of a shaft 64 journaled in the totalizer frame 65 and having secured thereto a group of retaining arms 69 in alignment with the group of transfer pawls 81, but normally held out of contact therewith by a torsion spring 741. Also secured to this shaft 64 is an arm 68 (Fig. 1) cooperating with a cam 149 carried by the turn-to-zero shaft 73. During the first part of the rotation of the shaft 73, the cam 149 rocks the 110 arm 68 and, consequently, the shaft 64 and arms 69 clockwise (Fig. 3), whereby the upper ends of the retaining arms 69 will contact, raise and hold the transfer pawls 81 in such positions that the shoulders on the transfer pawl supporting arms 80 may assume their normal positions after having been tripped by the transfer projections 79 during the turn-to-zero movements of the 115 totalizer wheels. Near the end of the rotation of the turn-to-zero shaft 73, the cam 149 permits the arm 68, shaft 64 and retaining arms 69 to be rocked to their normal positions by the spring 741, thus permitting the transfer pawls 81 to be lowered to their 120 normal positions, resting on the shoulders of the transfer pawl supporting arms 80. 125

This mechanism is substantially the same as that shown and described in applicant's co-pending application, Serial No. 458,509, 130

filed April 4, 1921; and is also substantially the same as that clearly illustrated, but not described, in the U. S. Letters Patent, No. 748,261, granted to Joseph P. Cleal on December 29, 1903.

For the purpose of counting the number of items or amounts entered in the machine at any time before the total is taken, counters are provided to be actuated for each item or amount-entering operation. The frame 150 of the counters is shown in Figs. 1, 5 and 9 supported on the printer frame 53 by means of bracket plates 162 as shown. The counters comprise separately operable counter wheels 151 rigid with ratchet wheels 152 (Fig. 6) loosely mounted on a turn-to-zero shaft 153 supported in the counter frame. The counter wheels are actuated by pawls 154 and 1154 pivoted on an arm 155 pivoted on a stud 163 carried by the counter frame. A link 156 connected to said arm and to an arm 157 fastened to the key-coupler trunnion 56 operates said arm and pawls during each item operation of the machine. Any of the well known and suitable transfer mechanisms may be used to transfer from the lower order wheel 151 to the higher order wheel 151.

The counters (Fig. 9) are turned to zero during each total printing operation by the turn-to-zero shaft 153 which is rotated by the segment-gear 141, hereinbefore described, and intermediate gears 158 and 159 supported on studs on the counter frame, which in turn rotate gear 160 secured to the turn-to-zero shaft 153. The counter wheels 151 are provided with the usual retaining pawls 161.

In Fig. 1 the totalizer is shown in its normal position, in which position it is kept during operations in which a plurality of items are printed and totaled, the result of which is shown in Fig. 12. When the totalizer is in this position the pawl 154 (Fig. 5) for the left hand counter wheel 151 is rendered ineffective by a link 165, connected to an arm 166 pinned to a shaft 167 carrying an arm 168 moved clockwise (Fig. 2) by a pin 169 on the totalizer frame 65 as the totalizer is rocked into engagement with its actuators 39.

During processes of multiplication, when multiplying by the units order multiplier, the totalizer is left in its normal position and the units multiplier is set up in the right hand counter wheel 151 (Fig. 5). The totalizer is then shifted one step to the right (Fig. 1) and the keys 30 are operated as required and the dimes multiplier is set up in the left hand wheel 151. The totalizer is provided with a handle 170 to shift it into different positions.

For the purpose of properly alining the totalizer pinions with the totalizer actuators

39, the left hand side member of the totalizer frame is provided with an aliner 171 (Figs. 1 and 2) adapted to cooperate with notches in an aliner plate 172 suitably supported on a yoke-shaped bracket 173 provided with depending stops 174 for engagement with pins 175 on the totalizer actuators to arrest the same in home position.

When the totalizer is shifted to the right a pin 180 (Fig. 5), corresponding to the pin 169, is moved into alinement with an arm 181 connected by a sleeve 182 to a yoke 183 integral with the arm 1166 (Fig. 6) connected by the link 1165 to the pawl 1154 for the right hand counter wheel 151. The shifting of the totalizer to the right, as above mentioned, also moves the pin 169 out of alignment with the arm 168 fast on the shaft 167. When the totalizer is rocked when in this position the pawl 1154 (Fig. 5) is disabled by the pin 80 and the left hand pawl 154 is rendered effective because the pin 169 cannot strike the arm 168.

In Fig. 4 an extra transfer cam 83 is provided and the rollers on the lever 76 are extended to the right so that the totalizer will be rocked into engagement and the transfers effected when the totalizer is in either of its positions.

A push key 190 (Figs. 1 and 7) may be provided to set a type wheel to print the letter M when processes of multiplication are performed. This type wheel is carried on the outer tube of tube line 42 to which an arm 192 is connected. This arm is operated by an arm 193 carried by the push key 190. A spring 194 normally holds the push key in the position shown, in which position the letter M is not printed. When a grand totalizer is employed this key operates to throw out the grand totalizer in the usual manner through the link 191 and connections not shown in this application.

On the receipt strip illustrated in Fig. 10, there are printed five amounts ".50" with the letter "M" in front of each one of them. At the bottom of this strip under the word "Total" are the figures "11.50". This total represents .50 multiplied by 23. The reason for the .50 being printed in the same column in each case, is that in this preferred form, the totalizer is to be shifted relatively to the actuating racks, and since the type wheel gears 40 are connected directly to the actuating racks, the type wheels are not shifted. As the same keys are operated three times with the totalizer in the normal position, and twice with it in its shifted position, the same actuating racks are operated each time, and the result accumulated in the totalizer is 11.50, and the amount printed for all five operations is in a single column.

The actual multiplying of 50¢ by 23 is accomplished in the following manner:

Referring to Fig. 1, it will be noted that the

machine is broken away, and that the full keyboard is not shown, the '10¢' key being the highest denominational order key shown; however, in applicant's co-pending application, Serial No. 293,141, previously referred to in this application, there is disclosed a full keyboard having a capacity of 1¢ to \$30.00.

Now to multiply 50¢ by 23, the operator first makes sure that the totalizer is in the position shown in Fig. 1. He then depresses the 50¢ key three times, which accumulates into the totalizer 150, or in other words, \$1.50. During this operation the key coupler 31 is oscillated three times, and the link 156 (Fig. 6) causes three movements of the pawl 1154 associated with the units order counter wheel 151, whereby three steps of movement is given to this counter wheel so that it indicates '3'. The operator then, by means of the handle 170, shifts the totalizer to the right one step and presses the 50¢ key two more times, thus adding into the totalizer 1000, or \$10.00. During this operation the key coupler 31 receives two oscillations, and the link 156 (Fig. 6) moves the pawl 154 associated with the 'Tens' counter wheel 151 two times, thus giving two steps of movement to the 'Tens' counter wheel 151 so that it shows '2'. These two wheels 151 (Fig. 5) now indicate '23', showing that the multiplier was '23'. The totalizer is now reset to zero and the total printed, thus indicating in whole numbers '1150', or in decimals \$11.50, as indicated by the receipt strip shown in Fig. 10.

In the form disclosed in Figs. 14 to 17 the totalizer is not movable laterally, the multiplying being accomplished by providing a larger number of totalizer actuators than the number of digits in the largest amount that can be entered in the totalizer and by employing different combinations of actuators when performing processes of multiplication.

One of the segments actuated by the keys is shown at 200 (Figs. 17 and 18). Three such segments are employed, each in mesh with a pinion 201 fixed to a shaft 202 extending across the width of the machine. Pinions 203 are splined to the shafts 202 for rotation therewith and relatively lateral movement thereon. These pinions 203 are adapted to mesh with totalizer actuators 204 (Figs. 16 and 18) loosely mounted on a supporting rod 205. In the embodiment disclosed, five totalizer actuators are provided, with any three of which the pinions 203 and the totalizer may be engaged during each operation involving an entry of an amount in the totalizer. The units keys may therefore actuate the units, dimes or dollars totalizer wheels. Thus, it is possible to carry out a process of multiplication in which the multiplier may consist of three digits.

A U-shaped frame 210 (Figs. 15, 16 and 18) encloses the pinions 203, the legs of said frame being perforated to receive the shafts 202. Spacing sleeves 211 between the legs of said frame and said pinions hold the pinions in properly spaced relation with respect to each other and the frame. An aliner 212 is secured to said U-shaped frame 210, the alining edge of which is provided with three notches 213 normally in line with the units, tens and hundreds pinions 203 to permit the totalizer actuators 204 in mesh with said pinions to function. The other actuators are alined in home position regardless of the position of the frame 210. A handle 214 (Figs. 14 and 15) extending through a slot in the cabinet constitutes a means by which the pinions 203 may be positioned, the different poistions being indicated on the cabinet below the slot.

Counting means, involving counter wheels 164, is provided. The counter wheels mounted in a frame 215 (Figs. 15 and 16) may be turned to zero by the same means as that used to turn the counter wheels 151 to zero, as shown in the first form (Fig. 9.) A counter actuating pawl 216 is flexibly supported on an arm 217 slidably and pivotally mounted on a spacing sleeve 218 on a rod 223 carried by forward extensions of the counter frame 215. Mounted on this rod 223 and held against lateral movement by the sleeve 218 is an arm 219 connected to the link 156 by a long pin 220 carried by the link 156 and extending through the arm 217. The link 156 is operated from the key coupler as in the first form (Fig. 6) and the pin 220 is long enough to engage the arm 217 in any one of the shifted positions of said arm. An aliner bar 221 secured to the counter frame is notched to cooperate with an aliner 222 on the arm 217 to properly aline the pawl 216 with the counter wheels 163.

A bar 225 secured to the frame 210 is provided with a vertically extending arm 226 provided with a curved slot 227 to receive a pin secured in the arm 217. This pin is provided with a retaining flange 228 to hold the arms 217 and 226 against relative lateral movement. As the handle 214 is moved into the different positions indicated, the arm 217 and pawl 216 are moved to select the counter wheel 164 appropriate to such position.

The manner in which 50 is multiplied by 23, when using the mechanism disclosed in the modified form shown in Figs. 14 to 18, will now be described.

In Fig. 15 the totalizer actuators 204 have been marked 'Units', 'Tens', 'Hundreds', 'Thousands', and '10-Thousands'. The operator first makes certain that the handle 214 is in the '1' position (Fig. 14), he then depresses the 50¢ key three times. During this operation the differential segment 200 (Figs. 17 and 18) associated with the 'Tens' actuator 204 is moved to the '5' position

- three times, and through the gear 201, shaft 202, and pinion 203, the 'Tens' actuator 204 is moved three times, five steps at a time, thus adding into the totalizer by means of the 'Tens' wheel, "15", and the totalizer wheels now stand as follows: 'Hundreds' wheel '1', 'Tens' wheel '5', and 'Units' wheel '0'. During this operation the key coupler 31 is given three oscillations, and
- 10 the pawl 216 through the link 156 is raised and lowered three times, and since this pawl is in cooperation with the 'Units' counter wheel 164, that wheel is given three steps of movement to indicate '3'. The operator
- 15 now shifts the handle 214 to the '2' position (Fig. 14). In shifting the handle 214 from the '1' to the '2' position, the frame 210 is moved to the left (Figs. 15 and 18), thus moving the pinions 203 to the left one step,
- 20 so that they now engage the 'Tens', 'Hundreds' and 'Thousands' actuators 204. The operator now depresses the 50¢ key twice, thus operating the 'Tens' order differential segment 200, which, through its associated
- 25 pinion 201, and shaft 202, rotates the pinion 203, now in mesh with the 'Hundreds' order actuator 204, thus causing this actuator to be given two movements of five steps each, thus adding ten units into the 'Hundreds' order totalizer wheel. Through the regular totalizer transfer mechanism '1' is added into
- 30 the 'Thousands' order totalizer wheel. The totalizer wheels now stand as follows: 'Units' wheel '0', 'Tens' wheel '5', 'Hundreds' wheel
- 35 '1', and 'Thousands' wheel '1', so that it now contains the product of 50 multiplied by 23, which is 1150 in whole numbers, or \$11.50 when using the decimal system.
- As the handle 214 was shifted to the left
- 40 (Fig. 15) prior to multiplying "50" by "2", the bracket 226 and pawl 216 were shifted to the left so that the pawl 216 cooperated with the 'Tens' order counter wheel 164, and as the key coupler was operated twice, the
- 45 pawl 216 turned the 'Tens' order counter wheel 163 two steps. The multiplier indicator wheels 163 now show '23'.
- The product is obtained by turning the totalizer wheels to zero and setting up on the printer in the manner previously described, the amount 1150 or \$11.50. During this total printing operation the counter wheels 164 are turned to zero in the manner previously described.
- 50 To multiply the number '456' by '123', the operator first makes certain that the handle 214 is in the '1' position, so that the pinions 203 will be in the positions shown in Figs. 15 and 18; he then depresses the amount keys representing '456' three times, so that this amount '456' is added into the totalizer by means of the 'Units', 'Tens' and 'Hundreds' actuators 204, and the totalizer then reads "1368". During this operation the pawl 216 moves the 'Units' order counter wheel 164
- three steps to indicate '3'. The handle 214 is then shifted from the '1' to the '2' position, thus shifting the pinions 203 so that they mesh with the 'Tens', 'Hundreds' and 'Thousands' actuators 204, and the pawl 216 is moved into cooperation with the 'Tens' order counter wheel 163. The operator now depresses the amount keys representing '456' two times, thus adding into the totalizer '9120', and the totalizer now stands at '10488'. The pawl 216 operates the 'Tens' order counter wheel 163 two steps, so that the counter wheels now show '23'. The operator then moves the handle 214 from the '2' to the '3' position, thus moving the pinions 203 so that they now mesh with the 'Hundreds', 'Thousands' and '10-Thousands' actuators 204, and the pawl 216 is in cooperative relationship with the 'Hundreds' order counter wheel 164. The operator now depresses the keys representing '456', once, thus adding into the totalizer '45600', and the totalizer now reads '56088'. The pawl 216 operates the 'Hundreds' order counter wheel 164 one step, and these counter wheels now show '123', which indicates the multiplier. The product '56088' now in the totalizer may be printed in the manner previously described, and the totalizer and multiplier indicator returned to zero in the manner also previously described.
- Machines constructed in accordance with the disclosures herein may be employed as ordinary itemized receipt printing cash registers, the counter wheels in this instance indicating the number of items entered in the machine at any time before a total is taken. When the counter wheels 163 are used as an item counter, any of the well known forms of transfer devices may be used to transfer from the lower order wheel to the next higher order wheel. Such machines may be used to obtain products and to print the same. The multiplicand is set up on the keyboard and indicated by the usual indicators 32. The multiplier is accumulated on the special indicating counter wheels 151 or 163. When the multiplier consists of a plurality of digits the totalizer in the first form, and the handle 214 in the second form, must be shifted so as to select the proper totalizer pinions and counter wheels 151 or 163 for operation.
- While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the claims which follow.
- What is claimed is:
1. The combination of a totalizer, counter wheels for counting the number of actuations thereof, means for recording the amount ac-

- cumulated on the totalizer, recording operating means, and means operated by said recording operating means for turning the counter wheels to zero.
- 5 2. The combination of a totalizer, counter wheels for counting the number of actuations thereof, means for recording the amount accumulated on the totalizer, recording operating means, and means operated by 10 the recording operating means for turning said totalizer and counter wheels to zero.
3. In a machine of the class described, the combination of denominational groups of amount keys; a differentially adjustable member associated with each group of keys and adapted to be operated thereby; a totalizer; actuators therefor, greater in number than the number of adjustable members; connections intermediate said members and certain 15 of said actuators, said connections including two sets of gears mounted on shafts to turn therewith; means for shifting one set of gears laterally relatively to said shafts to disconnect said gears from said certain actuators and to connect them, respectively, with certain other actuators, so that the same amount represented by the keys operated may be entered into different denominational orders of the totalizer.
- 20 4. In a machine of the class described, the combination of amount keys; differentially adjustable members operated thereby; a totalizer; actuators therefor; connections intermediate said members and certain of said actuators, said connections including one set of gears meshing with said members and another set of gears meshing with the certain actuators, whereby the movement of said members under control of said keys is imparted to said certain actuators; means for shifting one set of gears laterally relatively to said actuators to disconnect them therefrom, and to connect them with other actuators, so that the same amount represented by 25 the keys operated may be entered into different denominational orders of the totalizer; a plurality of counting elements; a single actuator therefor adapted to be shifted into operative relation with any of said counting elements by said gear shifting means, and means operated by depression of said keys to operate the counting element actuator.
5. The combination of a totalizer, actuators therefor, means laterally slid able to control the actuators to enter the same amounts in different denominations of the totalizer, means to engage the totalizer with and disengage it from the actuators, a plurality 30 of counter wheels, operating means for the counter wheels shiftable with the slideable means to selectively operate the counter wheels, and connections between the totalizer and counter operating means to 35 operate the counter operating means as the

totalizer is being engaged with the totalizer actuators.

6. In a multiplying machine having means to retain the multiplier and means to accumulate the product of the numbers being multiplied, the combination of means to record the product, means to return the multiplier retaining means to zero, and a common drive to actuate the recording means and the returning means during the same cycle. 75

7. In a multiplying machine, means to multiply a multi-denominational multiplicand by a multi-denominational multiplier, a set of amount keys, means whereby the denominational value of said keys may be changed during such a multiplying operation, and a printing device to record the part of the product entered during each cycle of the operation. 80

8. In a multiplying machine, means to multiply a multi-denominational multiplicand by a multi-denominational multiplier, a set of amount keys, means whereby such a multiplying operation may be performed by depression of the amount keys, means whereby the denominational value of said keys may be changed during the operation, and a printing device to record the part of the product entered by each depression of the amount keys during the operation. 85

In testimony whereof I affix my signature.
